UNITED STATES PATENT OFFICE.

WILLIAM E. DYRE, OF WASHINGTON, DISTRICT OF COLUMBIA.

SIGNAL.

SPECIFICATION forming part of Letters Patent No. 439,492, dated October 28, 1890.

Application filed May 22, 1890. Serial No. 352,730. (No model.)

To all whom it may concern:

Be it known that I, WILLIAM E. DYRE, a citizens of the United States, residing at Washington, in the District of Columbia, have invented certain new and useful Improvements in Signals; and I do hereby declare the following to be a full, clear, and exact description of the invention, such as will enable others skilled in the art to which it appertains to make and use the same.

My invention relates to signals, particularly to that class known as "pneumatic signals," and is designed for use on vehicles in general, though principally on bicycles, to which it is especially adapted.

It has among its objects the production of a cheap, durable, and attractive device capable of automatically sounding an alarm, when desired, with a marked degree of promptness and efficiency.

The invention will be hereinafter described, and particularly pointed out in the claims.

In the accompanying drawings, which form part of this specification, Figure 1 represents a side view of a bicycle with my invention applied in operative position; Fig. 2, a front view of the signal; Fig. 3, a side view thereof; Fig. 4, a central vertical section of same, and Fig. 5, a front view of an operating-lever applied to the handle-bar of a bicycle.

Reference being had to the drawings and the letters thereon, A represents a cylinder, preferably of cast metal, open at one end, as shown in Fig. 4, and having an annular enlargement or bead a encircling the periphery of its open end. Cast integral therewith is a projection B, located on the back of the cylinder and extending from the extreme top to near the bottom thereof, having a flat face, as b, and provided with parallel apertures C, piercing it from end to end, and serving to secure the device in position.

To the head of cylinder A, immediately above an opening c therein, is secured a whistle D, or signal of any description, while over the opposite end of said cylinder is fitted an elastic diaphragm E, held in position by a metallic ring F, having a concave inner surface d, adapted to engage bead a on the cylinder with the elastic diaphragm between.

To one side of the cylinder is riveted or otherwise secured a bracket of cast-steel G, having an outward bend e at a point slightly above the open end of the cylinder to afford space for the adjustment of ring F. Extending downward a suitable distance said bracket doubles itself about one-third of its entire length, at which point it makes another angle toward the center, terminating in an enlargement H, drilled, as at f, to afford a bearing 60 for a reciprocating rod, as will hereinafter appear.

Near the lower extremity of bracket G, in the two parallel members thereof, is loosely journaled an axle g, forming part of wheel 65 I, which is encircled by a rubber tire h, as shown.

On the face of wheel I, eccentrically located, is a wrist-pin i, which engages a link J, formed on the lower end of rod J' for the purpose of 70 converting the circular motion of wheel I into a reciprocating movement of rod J'. This rod J' passes through aperture f, which affords it a substantial bearing, and terminates in a screw-cap j, serving as a plunger when the 75 signal is in use.

The construction of my invention being substantially as described, a convenient application of it to a bicycle is that illustrated by Figs. 1 and 5 of the drawings, whereby the 80 lamp-bracket K is utilized as a support for the signal. The bracket being formed of unusual length, with the additional material in the two ends below the customary binding-screw bent up as at k k and passing through 85 apertures C C of the signal, thus permitting a vertical movement of the latter on the former, which movement is controlled by a lever L, fulcrumed on the handle-bar of the machine, similar in all respects to the brake-lever except that the dependent rod l encircles and is secured to the head of the cylinder A instead of communicating with the brake. The attachment having been thus effected, the signal remains normally in the position shown 95 by Fig. 5, under the influence of the spring on the handle-bar. In this location the device is subjected to the least possible vibration, an advantage readily appreciated by wheelmen who have realized the annoyance 100

of a bell secured to the handle-bar of a machine, where the maximum vibration occurs, loosening the parts of the bell which, as a natural result, then rattle.

5 At the will of the rider my improved signal is set in operation as follows: The lever L is grasped by the fingers on the left hand of the rider and drawn toward the handle-bar against the action of the spring, thus communicating 10 a downward motion to the rod l and the signal secured thereto, until the tire h on wheel I comes in frictional contact with the rubber tire of the front wheel of the machine. The machine being in motion, wheel I will now re- 15 volve more or less rapidly according to its size, thrusting the plunger j into elastic diaphragm E, which is thus stretched, as shown by dotted lines in Fig. 4, forcing the air from the cylinder A through a whistle or other signal D in 20 a rapid succession of blasts, after which lever L may be released. The signal will then automatically disengage, at the same time resetting itself for future action, the latter re- 25 sult being due to the elasticity of diaphragm E, the constant tendency of which is to eject plunger j from the cylinder and leave it in readiness for a full and effective stroke the instant a signal may be desired.

As herein stated, preference is given, as far 30 as is expedient, to casting in the construction of the device; but I by no means limit myself to this form, as the cylinder A could advantageously be made from a section of tubing provided with a screw-cap bearing the signal, 35 or spun up from sheet metal, in which latter case one half of a whistle of the flat form could be made integral therewith, the other half being soldered below; nor do I limit myself to a bracket, as G, of a particular material or 40 shape, as any means of supporting the friction-wheel I for operating the plunger j may be employed without departing from the spirit of my invention.

Having thus fully described my invention, 45 what I claim is—

1. The herein-described pneumatic signal, consisting of an air-chamber having one end formed of an elastic diaphragm and a wind-instrument connected with said chamber, 50 whereby the air within the chamber can be made to render a signal upon the wind-instrument by force applied to the diaphragm in one direction only.

2. The herein-described combination of an 55 air-chamber, a wind-instrument connected therewith, an elastic diaphragm closing one end of said air-chamber, and a reciprocating plunger for impacting against the diaphragm.

3. The herein-described pneumatic signal, 60 consisting of an air-chamber having one end formed of an elastic diaphragm, a wind-instrument connected with said chamber, and a plunger having a convex head for impacting against the diaphragm.

65 4. The herein-described combination of a wind-instrument, an air-chamber provided

with a head, a band adapted to engage the head, and an elastic diaphragm held between said band and head adapted to receive the impact of a plunger for driving the air from the cylinder through the wind-instrument, rendering a signal thereupon.

5. The herein-described combination of an air-chamber having one end closed by an elastic diaphragm, a wind-instrument connected 75 with said chamber, a reciprocating plunger impacting against one side of the said dia- phragm, and a bracket connected with said chamber forming a guide for the said plunger.

6. The herein-described pneumatic signal 80 for bicycles, consisting of the air-chamber, a wind-instrument connected therewith, the elastic diaphragm closing one end of said air-chamber, and a reciprocating actuating de- 85 vice, one end of which is in close proximity with said diaphragm but not connected thereto, said reciprocating device also held from being thrown out of its closed relation with said diaphragm by momentum.

7. The herein-described pneumatic signal 90 for bicycles, consisting of the air-chamber having one end closed by an elastic dia- phragm and its opposite end communicating with the open air through a wind-instrument, of a reciprocating actuating device having 95 one end in close proximity to the said dia- phragm, said reciprocating device adapted to receive motion from one wheel of the bicycle, and together with the air-chamber movable into and out of operative position in respect 100 thereto.

8. The herein-described pneumatic signal for bicycles, consisting of the air-chamber having one end closed by an elastic dia- phragm and communicating with the open 105 air at its other end through a wind-instrument, and a reciprocating actuating device having a convex surface in close proximity to said diaphragm but not connected thereto, said actuating device being held from being 110 thrown out of its close relation to said dia- phragm by momentum.

9. The herein-described combination of a bicycle provided with a lamp-bracket having its lower end bent up, a signal supported upon 115 said bracket, a signal-operating mechanism, and means for throwing the latter in and out of contact with one wheel.

10. The herein-described combination of a pneumatic signal, a bicycle provided with a 120 lamp-bracket having its lower ends bent up, a vertically-movable signal secured thereon, an operating mechanism, and means for throwing the signal in and out of frictional contact with the periphery of one wheel.

11. The herein-described combination of a pneumatic signal, a bicycle provided with a lamp-bracket having its lower end bent up, an air-chamber provided with a projection thereon pierced by an aperture for engaging 130 the lamp-bracket, an elastic diaphragm, a wind-instrument, operating mechanism, and

means for throwing said mechanism in and out of contact with one of the bicycle-wheels.

12. The herein-described combination, with a bicycle having a lamp-bracket, of a signal provided with a friction-wheel for operating the same and movably supported on said bracket, a lever and its connecting-rod, the latter surrounding and secured to the head of the signal, whereby the signal may be re-

ciprocated on said bracket to move it into and out of operative position.

In testimony whereof I affix my signature in presence of two witnesses.
